UNITED STATES PATENT OFFICE.

LEO W. BRUNELL, OF FOXBORO, MASSACHUSETTS, ASSIGNOR OF ONE-THIRD TO BURT F. UPHAM AND ONE-THIRD TO EDWARD W. CALKINS, BOTH OF BOSTON, MASSACHUSETTS.

MEANS FOR TREATING SHEET MATERIAL WITH HEAT.

Application filed March 19, 1927. Serial No. 176,633.

This invention relates to novel means for treating sheet material, such as paper, with heat furnished by a gas burner, between which and the paper there is a relative movement. The invention is particularly useful in connection with the drying of ink and the neutralizing of static charges on paper passing through or from a printing press.

The invention will be best understood by reference to the following description, when taken in connection with the accompanying drawings of one specific embodiment thereof, while its scope will be more particularly pointed out in the appended claims.

In the drawings:

Fig. 1 is a side elevation of a portion of a printing press equipped with heat treating means exemplifying the invention;

Fig. 2 is a sectional view, on line 2—2 of Fig. 1;

Fig. 3 is a horizontal, sectional view, on line 3—3 of Fig. 1;

Fig. 4 is a somewhat conventional illustration of the entire press in side elevation, simply to show the general arrangement of the press, but omitting the novel features of the invention;

Fig. 5 is a vertical, sectional view of the valve, which, in conjunction with a pump, controls the flow of gas to the burner;

Fig. 6 is a vertical, sectional view of the pump;

Fig. 7 is a sectional view, on an enlarged scale, on line 7—7 of Fig. 1, illustrating the means for mixing gas and air to be supplied to the burner; and

Figs. 8, 9 and 10, are diagrammatic views illustrating the operation of the sheet-feeding means, in connection with the burner.

Referring to the drawings, and to the embodiment of the invention which is selected for exemplification, there is shown in Fig. 4 one type of press, in connection with which the invention may be used. The press includes the main frame 11, a feed table 12, a cylinder 13, a set of feed tapes 14, which receive the sheets one by one from the cylinder, and a reciprocating carriage 15, which travels on rails 16 and causes the tapes to deposit the sheets one by one on a jogger 17.

The mechanism for controlling the operation of the tapes will now be described, reference being had at first to Fig. 8. Each

tape is an endless band, which extends part 55 way around each of a set of rollers 18, 19, 20 and 21. The rollers 18 and 19 are mounted on the press frame (see Fig. 3), while the rollers 20 and 21 are mounted on the carriage. There are individual rollers 21, one for 60 each tape, and each of these rollers is carried by a bracket 22 secured to a transverse tie-piece 23, which is a part of the carriage 15. At the other end of the carriage, there is another tie-rod 24 (see Fig. 1) connecting 65 the two sides of the carriage. The carriage is equipped with rollers 25 (see Fig. 2), which run on the rails 16, respectively. Brackets 26, secured to the rails, and overlying the sides of the carriage (see Fig. 2), 70 prevent the carriage from being lifted. The carriage is reciprocated by mechanism including racks 27 on the under side of the carriage, and meshing with gears 28.

As herein shown, the reciprocating movement of the carriage is utilized to impart an intermittent movement to the tapes, the arrangement being such that that portion of the tapes on which the sheet rests (see Figs. 8, 9 and 10) moves forward with the carriage, and at the same speed, whereas during the backward movement of the carriage, the tapes remain stationary. This is conveniently accomplished by providing two ratchets 29 and 30 (see Fig. 8), one secured 80 to the roller 18 and the other to the roller 20, and cooperating with these ratchets are pawls 31 and 32, respectively. As clearly shown in Fig. 8, one ratchet and its associated pawl is so arranged that it is active, 85 while the other is inactive. Furthermore, the pawls and ratchets are so arranged that, during the forward movement of the carriage from the position shown in Fig. 8, to and beyond the position shown in Fig. 9, 95 the pawl 31 does not permit the ratchet 30 and roller 20 to rotate, whereas the pawl 32 permits the ratchet 29 and roller 18 to rotate contra-clockwise, as shown in Fig. 9. Accordingly, during the forward movement 100 of the carriage, the upper part of the tape which sustains the sheet travels forward with the carriage, and at the same speed. On the other hand, during the backward travel of the carriage, as illustrated in Fig. 10, the pawl 32 now holds the ratchet 29 and roller 18 against rotation, and the pawl 31 permits rotation of the ratchet 30 and

rollers 20 clockwise. Accordingly, that portion of the tapes which sustains the sheet remains stationary. All of this, of course, is well known, and requires no further description.

During the forward motion of the carriage, the front edge of the sheet is against one or more stops 33 mounted on the carriage, but when the sheet is brought to a 10 position above the jogger-board or table 17, the stops 33 are lifted (see Fig. 10), and another stop 34, also mounted on the frame of the machine, swings from the horizontal position represented in Figs. 8 and 9 to 15 the vertical position represented in Fig. 10, and thus prevents backward movement of the sheet, while the carriage is travelling backward, or at least during the early part of the backward travel. The operation of 20 these stops, likewise, is all old and well-known.

I will now describe the attachment with which my invention is concerned, reference being had at first to Fig. 3. A gas bar 25 comprising a pipe 35, extending transversely of and beneath the path of the sheet, and provided with perforations 36 and thereby constituting a burner, is appropriately mounted on the carriage, as by clamps 37, 30 about the gas bar, these clamps being provided with rearwardly extending shanks or rods 38, suitably secured to the tie-piece 23, as by blocks 39, into which the rods extend and to which the rods are secured as by set- 35 screws 40. This provides an adjustable mounting for the gas bar, permitting the same to be placed in the most advantageous position with relation to the path of the paper. Inasmuch as the paper, in passing 40 over the gas bar contacts therewith (see Fig. 10), the perforations 36 are located at the forward side of the gas bar, so that there is no danger of the paper being scorched.

45 The gas bar receives its supply through a pipe 41 from a mixing chamber 42 (best shown in Fig. 7), with which there is associated a gas nozzle 43 and an adjustable valve 44 of known construction. The nozzle 43 herein is screwed into a nipple 45, the arrangement being such that a nozzle whose orifice is of the correct cross-sectional area may be selected by trial.

50 Inasmuch as the burner is to be extinguished and relighted automatically, as will hereinafter appear, there is associated with the gas bar a pilot burner 46 (see Fig. 3), appropriately supported on the pipe 41, as by clamps 47 and 48 (see Fig. 1), the outlet 55 orifice of the pilot being adjacent one end of the row of perforations 36, so as to light and relight the main burner. A shield 49 (see Fig. 3), about the end of the pilot and about a portion of the gas bar, and secured 60 to the latter, as by screws 50, prevents the

7 pilot light from being extinguished accidentally. The tube which constitutes the pilot is appropriately connected, as by a flexible conduit such as a rubber hose 51 (see Fig. 1) to a source of supply of gas 7 (not shown).

Efficient and economical operation of the gas bar is assured by novel means now to be described, reference being had at first to Fig. 1. An appropriate pump 52, which 7 serves to boost the pressure of the gas on its way to the burner, is suitably mounted on a reciprocating carriage, as by means of a clamp 53, which clamps the pump on the transverse tie-rod 24. In the present example, this pump is a common form of rotary pump (best shown in Fig. 6), and comprises a casing or stator 54, having an inlet 55 and an outlet 56 between which there is a rotor 57, having blades 58. This pump is driven by appropriate mechanism, which causes it to operate during the backward travel of the carriage, but to remain inactive during the forward travel. Herein, this is conveniently accomplished by driving the pump from the tape roller 20 (see Fig. 1) by sprocket wheels 59 and 60 and a chain 61 connecting them. In this connection, it will be remembered that the rotation of the tape roller 20 is intermittent, and it is rotated only during the backward travel of the carriage, as will be evident from an examination of Fig. 10.

65 The pump inlet is connected as by a shut-off cock 62 and a flexible conduit, such as a rubber hose 63, with the gas supply, while the pump outlet is connected by a similar rubber hose 64 with the nipple 45, which, it will be remembered, conducts the gas to the nozzle in the mixing chamber. There is associated with the pump an automatic valve 65 (best shown in Fig. 5), so constructed and arranged as to be regulated, opened and closed, by the operation of the pump. In the present example, this valve 70 is placed between the outlet side of the pump and the burner, so that it is opened by the pressure of the gas which flows through it from the pump; but this location is not essential, as it is evident that it equally well might be connected to the inlet side of the pump, in which case it would be opened by the suction of the pump.

75 The valve employed in the present example comprises a valve body or casing 66 (see Fig. 5), having an inlet 67, an outlet 68 and a valve seat 69 therebetween. A valve 70, cooperating with the seat 69, is carried by a swinging arm 71 mounted on a pivot 72, and normally closed by a spring 73. One end of this spring is seated against a nut 74, which is screwed onto a threaded shank 75, by means of which the valve 70 is secured to the arm 71. Adjustment of the degree of resistance presented by the

spring to the opening of the valve under the pressure of the gas is conveniently effected by an adjustably mounted abutment 76 for the other end of the spring. Herein, 5 this abutment is mounted to slide in slots 77 presented by a threaded plug 78, which is screwed into the valve casing 66. Adjustment of the abutment to vary the strength of the spring is conveniently accomplished 10 by an adjusting screw 79, threaded into the plug 78 and having its inner end engaging the abutment 76.

It should now be evident that the pump and the valve, by their cooperative action, 15 not only cause gas to be supplied to the burner only during the backward movement of the carriage, but also regulate the pressure of the gas in accordance with the speed of the press. Therefore, there is a resultant 20 efficiency and economy of operation of the gas bar, and there is no danger of the sheet becoming ignited, no matter if the press should slow down and stop, even when the sheet is passing over the gas bar. It should 25 also be evident that these advantages are obtainable by the use of the described attachment, in connection with presses of other types.

Having thus described one embodiment of 30 the invention, but without limiting myself thereto, what I claim and desire by Letters Patent to secure is:

1. In a printing press, the combination of 35 a gas burner, means for causing a relative movement of the sheet of paper and the gas burner, a pump for pumping gas to said burner, and means to cause said pump to pump gas to said burner only when the press is operating.

40 2. In a printing press, the combination of a gas burner, means for causing a relative movement of the sheet of paper and the gas burner, a pump for pumping gas to said burner, and means to drive said pump at a speed proportioned to the speed of the press.

45 3. In a printing press, the combination of a gas burner, means for causing a relative movement of the sheet of paper and the gas burner, a pump for pumping gas to said burner, and means to drive said pump at a speed proportioned to the speed of the press and to cause said pump to stop when the press stops.

50 4. In a printing press, the combination of a gas burner, means for causing a relative movement of the sheet of paper and the gas burner, a pump for pumping gas to said burner, and means to cause said pump to supply gas to said burner during said movement and to stop said pump during another part of the cycle of the press.

55 5. In a printing press, the combination of a gas burner, reciprocating means for causing a relative movement of the sheet of paper and the gas burner during one stroke of said

means, a pump for pumping gas to said burner, and means to cause said pump to supply gas to said burner during said stroke and to cause said pump to stop during the other stroke of said reciprocating means. 70

6. In a printing press, the combination of means including a reciprocating carriage and an endless sheet-supporting band to cause a feeding movement of said band and the sheet carried thereby during the forward 75 stroke of said carriage, and to cause the sheet-supporting portion of said band to remain fixed during the backward stroke of said carriage, a gas burner carried by said carriage and moved thereby backward beneath said sheet during the backward stroke of said carriage, a pump for pumping gas to said burner, and means to cause said pump to pump gas to said burner only during said backward stroke. 80

7. In a printing press, the combination of a gas burner, instrumentalities including an endless band, a roller over which said band passes, and means for rotating said roller intermittently to cause an intermittent feeding movement of the sheet-supporting portion of said band, and to cause a relative movement of said burner and the sheet, a pump for pumping gas to said burner, and means connecting said roller to said pump to cause the latter to drive the former. 85

8. In a printing press, the combination of a burner, means including an intermittently moving part for causing a relative movement of the sheet and said burner, a pump for pumping gas to said burner, and a driving connection between said pump and said intermittently moving part. 90

9. In a machine for heat-treating sheets, the combination of a gas burner, means for causing a relative traversing movement of said burner and the sheet, a gas pump having a gas inlet and a gas outlet to said burner, a valve associated with said pump and responding to variations of gas pressure produced by said pump and in turn controlling the flow of gas to said burner, and means connected with the first-mentioned means for causing said pump to be driven intermittently in timed relationship with said traversing movement. 105

10. In a machine for heat-treating sheets, the combination of a gas burner, means for causing a relative traversing movement of said burner and the sheet, a gas pump for pumping gas to said burner, a self-closing valve associated with said pump and moving in response to pressure fluctuations produced by said pump and in turn controlling the flow of gas to said burner, and means for driving said pump at speeds varying with the speed of said movement and for stopping said pump when the machine stops. 115

11. In a machine for handling sheet material, the combination of a gas burner, feed- 120

ing means for feeding the material past said burner, pressure-responsive means for controlling the flow of gas to said burner, and means for varying the pressure applied to said pressure-responsive means in accordance with the feeding rate of said feeding means.

12. In a machine for handling sheet material, the combination of a gas burner, feeding means for feeding the material past said burner, pressure-responsive means for controlling the flow of gas to said burner, and means for applying pressure to said pressure-responsive means when said feeding means is operating and for relieving the pressure on said pressure-responsive means when said feeding means is not operating.

13. In a machine for handling sheet material, the combination of a gas burner, means for causing a relative movement of the sheet and said gas burner, pressure responsive means for controlling the flow of gas to said burner, and means for varying the pressure applied to said pressure responsive means in

accordance with changes in the relative positions of the sheet and said gas burner.

14. In a machine for handling sheet material, the combination of a gas burner, means for causing a relative movement of the sheet and said gas burner, a pressure responsive valve for controlling the flow of gas to said burner, a pump for pumping gas through said valve to said burner, and means for modifying the operation of said pump in accordance with changes in the relative positions of the sheet and said gas burner.

15. In a machine for handling sheet material, the combination of a gas burner, means for causing a relative movement of the sheet and said gas burner, a pump for pumping gas to said burner, and means for modifying the operation of said pump in accordance with changes in the relative positions of said sheet and said gas burner.

In testimony whereof, I have signed my name to this specification.

LEO W. BRUNELL.
